United States Patent Office.

HENRY K. SMITH, OF BOSTON, MASSACHUSETTS.

Letters Patent No. 70,278, dated October 29, 1867.

IMPROVEMENT IN SLEIGH-BELLS.

The Schedule referred to in these Letters Patent and making part of the same.

TO ALL PERSONS TO WHOM THESE PRESENTS SHALL COME:

Be it known that I, HENRY K. SMITH, of Boston, in the county of Suffolk, and State of Massachusetts, have invented a new and useful Improvement in Sleigh-Bells, or in connecting such a bell and its tongue together, and to a strap or its equivalent; and, I do hereby declare the same to be fully described in the following specification, and represented in the accompanying drawings, of which—

Figure 1 is a longitudinal section of a bell and strap applied together in accordance with my invention.
Figure 2 is a top view, and

Figure 3 a side elevation of the hook for supporting the tongue to the bell.

One mode of connecting the tongue-hook to a bell has been to cast the bell body upon the shank of the hook; but this method of conjoining the two renders the shank easily separable from the body. Another method has been to make a hole in the corner of the bell and pass the shank up through such hole and hook it about the projection extending upward from the crown of the bell; in which case the projection served in part as a means of fixing the bell to its strap. The last-described application of the tongue-hook is an expensive one, and causes the bent part or portion of the shank which encompasses the projection to be in the way of fixing the bell to its strap. Besides, it is objectionable on account of appearance.

In carrying out my improvement I make the tongue-hook A with an eye, a, to receive the shank b of a rivet, B. This rivet is to be introduced through the said eye and the crown c of the bell C, and thence through the strap D, after which the end of the shank of the rivet should be upset. The head of the rivet may be either above or below the crown c, and the rivet may go through a metallic washer, d, arranged on its shank, and below the eye of the tongue-hook. In fig. 2 the tongue of the bell is shown at E as suspended on the hook, which, after being fixed to the bell and carried through the tongue-eye, should be bent up toward the crown so as to hold the tongue in connection with the body of the bell.

By my invention or improvement not only will the tongue-hook be connected to the bell, but the latter will be connected with its fastening-strap by means of the rivet, the whole being so that the connection of the bell and the strap will be a very strong, efficient, and durable one.

What, therefore, I claim as my invention, is—

The improved construction of the tongue-hook, and arrangement of it, the rivet, the bell, and the strap, as described.
